UNITED STATES PATENT OFFICE.

SAMUEL C. GAULT, OF CINCINNATI, OHIO.

TOBACCO-CUTTER.

SPECIFICATION forming part of Letters Patent No. 249,831, dated November 22, 1881.

Application filed August 12, 1881. (No model.)

To all whom it may concern:

Be it known that I, SAMUEL C. GAULT, a citizen of the United States, residing at Cincinnati, Hamilton county, Ohio, have invented 5 a new and useful Improvement in Tobacco-Cutters; and I do hereby declare that the following is a full, clear, and exact description thereof, reference being had to the accompanying drawings, and the letters or figures of reference marked thereon.

My invention relates to devices for cutting plug-tobacco; and it consists in providing certain improvements in the construction of the same, which will hereinafter be fully described 15 and pointed out.

In the drawings hereto attached the device is shown as follows:

Figure 1 is a perspective view of the device. Fig. 2 is a side elevation of the inside of the frame C, with other parts in vertical longitudinal section. Fig. 3 is a perspective view of the knife and knife-head.

A is the lever by which the knife is actuated. B is the knife; B', the knife-head; C C, the frame-work, which consists of flanged plates set together with their flanges facing each other, leaving an inclosed cavity, which receives the knife and knife-head and part of the actuating-lever. c c c, &c., are the flanges 25 above named. Other parts as lettered will appear in the following general description.

The knife-head is provided at each end with friction-rollers E E, mounted on pins e e.

The frame-plates C C are provided with 35 curved slots F F, for receiving the said friction-rollers and furnishing bearings for the same. The lower side of these slots may be formed so as to serve as the bearing-faces of said rollers; or, as shown, auxiliary pieces of 40 soft metal may be set in and form said bearing-faces.

G G are the auxiliary pieces referred to. They are attached on the inside of the plates C C. The objects of these pieces G are to 45 avoid friction in case the rollers do not move easily, and to prevent wear. They are made preferably of brass.

It will be seen that the knife, being mounted in these slots, will move when cutting as the 50 form of the slots directs, and that this form, as shown, is such that at the first of the cut the blade moves slightly oblique, and at the finish it

has a nearly horizontal movement. This movement insures the cutting of the wrapper of the plug of tobacco. This is more difficult to do on 55 the lower than on the upper side of the plug, and therefore I form the slots F so as to give a nearly (and it may be fully) horizontal movement to the knife for a little distance just at the finish of the cut. The edge of the blade, as 60 shown, is crenated; but any other form may be used.

In order that the knife may move freely as directed by the slots, the actuating-lever at the point where the knife-head attaches to it is 65 slotted (see d) and sets loosely over the pin d'.

I, of course, do not desire to be limited to the precise form of slot F shown, as it may be varied to get a more or less oblique movement of the knife. If the form is an exact arc, 70 the lever A need not be slotted, provided the said arc has a proper concentric arrangement.

I am aware that it is not new to mount a knife in oblique guiding-slots and actuate it by means of a rack and toothed involute; also, 75 that it is not new to locate a knife in an inclined passage and raise it by a lever connected to the knife by means of a link, and lower it by forcing the short arm of the lever against the knife. These devices differ from 80 mine, in that my knife has a head, B', provided with a pivot-pin, which serves as a support or bearing for the short arm of handle or lever A, by means of which the knife is elevated or lowered without employing any secondary 85 parts, making a cheaper and better device than any now in use.

What I claim as new is—

1. In a tobacco-cutter, a knife mounted in oblique guiding-slots and having a head provided with a pivot-pin, for the purpose set forth, in combination with a handle having a slot for the reception of the pivot-pin, substantially as described, and for the purposes set forth.

2. A tobacco-cutter having flanged plates provided with oblique or curved slots for suspending the knife-head, in combination with a knife and knife-head, having bearing-pins for mounting the same within the curved slots, 90 and a pivot-pin, for the purpose set forth, and a handle or lever having a slot for the reception of the pivot-pin, substantially as described.

3. A tobacco-cutter having frame-plates pro-

vided with slots for guiding a knife-head, and lined with plates of soft metal, in combination with a knife-head having bearing-pins for mounting the same in said slots, and a pivot-
5 pin, for the purpose set forth, and an actuating lever or handle provided with a slot for the reception of the pivot-pin, substantially as described.

In testimony that I claim the foregoing I have hereunto set my hand this 9th day of 10 July, 1881.

SAMUEL C. GAULT.
